UNITED STATES PATENT OFFICE.

ISIDOR M. JACOBS, OF KANSAS CITY, AND WILLIAM CRAMER, OF ST. LOUIS, MISSOURI,
ASSIGNORS TO TRUCK, TRACTOR AND MANUFACTURING COMPANY, OF ST. LOUIS,
MISSOURI, A CORPORATION OF MISSOURI.

SUSPENSION DEVICE.

1,391,735.

Specification of Letters Patent. Patented Sept. 27, 1921.

Application filed March 17, 1920. Serial No. 366,660.

To all whom it may concern:

Be it known that we, ISIDOR M. JACOBS and WILLIAM CRAMER, citizens of the United States, residing, respectively, at the city of 5 Kansas City, county of Jackson, and State of Missouri, and at the city of St. Louis, in the State of Missouri, have invented certain new and useful Improvements in Suspension Devices, of which the following is a 10 specification.

This invention is a spring support for weighty objects, such, for instance, as the motor or the transmission or the radiator in selfpropelled vehicles or the like. The 15 weight of the radiator being so much less than that of the motor in such a vehicle, the size, weight, and strength of the springs and other parts will be varied according to the weight to be suspended. In principle, how- 20 ever, this device is the same regardless of the location in which used or the nature of the part or object to be supported thereby. It is, however, primarily designed and in- 25 tended as a spring support for the engine in motor-vehicles.

It is well known that the inequalities and rough places in roads that are traveled by such vehicles produce constant jarring, vibration, and wear and tear of the engine and 30 its bearings, and that this effect is very bad in the engine and is registered in every part thereof and results in unsatisfactory service and in the shortening of the life of the engine. These objections will be obviated by 35 this present invention.

In the accompanying drawings forming part of this specification, in which like numbers of reference denote like parts wherever they occur,

40 Figure 1 is a side elevation taken on the inside of the chassis of a motor vehicle;

Fig. 2 is a vertical sectional view, with some of the parts shown in Fig. 1 removed, and is taken on the line 2—2 in Fig. 3;

45 Fig. 3 is an elevational view looking at the parts in Fig. 1 from the right;

Fig. 4 is a top plan view; and

50 Figs. 5, 6, 7, 8, 9, 10, 11, and 12, illustrate various alternative forms of modifications of the supporting connection of the main device so as to adapt the same to receive and hold the foot or bracket of the engine intended for its attachment to the chassis or other supporting member.

Figs. 13 and 14 illustrate other modifications. 55

In the above description of the drawings, and hereafter in this specification, the support of an engine from the chassis of a motor vehicle is taken as an illustrative form 60 of the arrangement and use of this invention; but it is to be understood that this device is a spring support of any object from any kind of a support.

The chassis 1, being in the usual channel 65 form and having the flanges 2 and 3, is adapted to receive the arm 4 of angle-plate 5 and to allow the same to lie tightly there-against.

A longitudinal plate 6 is fastened to the 70 web of the channel or chassis 1 by bolts 7 and nuts 8, which ordinarily, but not necessarily uniformly, do not pass through arm 4 of plate 5, although they may do so if the arrangement of the parts in any given construction requires it. A plurality of bolt holes 9 is provided in arm 4 of plate 5 for use in case in any construction the space or 75 dimensions or other causes make it necessary to run the bolt 7 at a point opposite arm 4. 80 Otherwise, plate 6, and the engagement of angle-plate 5 with flange 3, is sufficient to hold angle-plate 5 very rigidly in connection with chassis 1 when the weight to be supported or borne has been placed upon rod 85 10, which is done by attaching the foot or bracket (not shown in the drawings) of the engine or other object to be supported upon plate or bracket 11. In certain instances, if desired, plate 6 may be omitted and dependence 90 placed entirely on bolt 7 and nuts 8.

The adjustability provided by the various possible arrangements, as herein described, of bracket 11, is augmented by the fact that socket 12 therein is screw-threaded and that 95 it is, therefore, movable upwardly or downwardly on screw 13. Socket 12 is located in a strong and heavy boss 14.

The above-described adjustability is enhanced by the fact that screw 13 passes 100 through nuts 15 and 16 and through the unscrewthreaded eyelet 17 in the arm 18 of rod 10.

Furthermore, adjustability toward or away from chassis 1 is provided by the nature of 105 the grip and support for rod 10, which support is firm and fixed when nuts 19 draw U-bolt 20 tightly against plate 21, thereby

forcing tight engagement of rod 10 in groove 22 of block 23. A groove 24 in plate 21 causes plate 21 and block 23, when thus drawn by U-bolt 20 and nuts 19, to operate 5 as a pair of jaws upon rod 10.

While the parts are being adjusted, an undue length of rod 10 will be present, but as soon as the degree of adjustment toward or away from the chassis 1 has been satisfactorily determined, the extra or superfluous metal 25 will be cut away at any desired point, as, for instance, even with the outside of chassis 1.

Since the weight is fastened to rod 10, 15 and since rod 10 can pull on springs 26, an excellent suspension is in this way provided. Upon the rebound, spring 27, located in socket 28 and bearing against angle-plate 5, assists springs 26 in absorbing the jar or 20 shock. A nipple 29 on the bottom of angle-plate 5 centers springs 27.

Slots 30 in the side and slots 31 in the top of bracket 11, afford means for attaching anything thereto and with a desirable 25 adjustability, in that, in some constructions, it may be found more suitable to use slots 30 and in others slots 31, and in some instances both sets of slots can be used.

Another optional arrangement or use of 30 this invention is depicted in Figs. 9 and 10 in which the foot or attaching bracket 32 of the engine or other object to be supported is shown provided with a lug 33, pierced by an eyelet 34 for the passage of screw 13 35 and held in place by nuts 15 and 16 in either of the alternative arrangements shown in the said figures. The same applies to Figs. 11 and 12.

The plate 6 permits the device to be located 40 at any point along chassis 1, and in that sense provides for longitudinal adjustment, while the slidability of rod 10 provides for lateral or transverse adjustment and the screw 13 provides for vertical adjustment, all for the purpose of allowing this device to be used as a support that will suit any and every type of engine or other object to be supported.

There is an advantage in bracket 11 being 50 in the shape of an angle, as it is, as that assists in providing adjustability, as shown in the figures of the drawings, by turning the same up or down.

The illustration in Fig. 1 in dotted lines of 55 the alternative position of rod 10 and the parts carried thereby shows that further adjustability is thereby provided.

In some instances the combination of 60 plate 6, angle-plate 5, and one of the springs or both of the springs 26 and a bolt or bolts in lieu of U-bolt 20, can advantageously be used, as shown in Figs. 13 and 14. In this construction the remarks heretofore made about the mode of attachment of plate 65 6 to chassis 1 or the omission of plate 6

and as to mode of attachment of angle-plate 5 to chassis 1 apply.

Figs. 13 and 14 are elevational views (partly in section) of a modification in which some of the parts hereinbefore described are omitted but the salient features of the channel 1, plate 6, angle-plate 5, and spring or springs 26 remain. For the U-bolt 20 is substituted a plain bolt 35 having a head 36. In engagement with the said bolt 35 is an 75 arm 37 of a cross-member 38 adapted to support radiator 39. The third-point suspension of a motor can likewise be well supported either upon cross-member 38 or by the motor bracket being placed with relation to spring or springs 26 or the same manner as arm 37 is shown in connection with the same in Fig. 14.

In the foregoing specification it should be understood that the word "longitudinal" relates to the channel 1 and not necessarily to the vehicle itself. Thus, in the description of this invention, longitudinal, as applied to the front or rear cross-part of the chassis, would be longitudinal with reference to the 90 chassis or channel 1, although transverse with relation to the vehicle as a whole.

Having thus described this invention, we hereby reserve the benefit of all changes in form, arrangement, order, or use of parts, 95 as it is evident that many minor changes may be made therein without departing from the spirit of this invention or the scope of the following claims.

We claim:

1. The combination of a support, a plate running longitudinally thereof, bolts for connecting the same together, a primary supporting member held by said support, a secondary supporting member borne by the said primary member, and spring means in relation to the said primary and secondary supporting members adapted to absorb shock and jar, and a tertiary supporting member, the said tertiary supporting member being adjustable vertically. 100

2. The combination of a support, a plate running longitudinally thereof, bolts for connecting the same together, a primary supporting member held by said support, a secondary supporting member borne by the said primary member, and spring means in relation to the said primary and secondary supporting members adapted to absorb shock and jar, and a tertiary supporting member, the said secondary supporting member being adjustable laterally. 115

3. The combination of a support, a plate running longitudinally thereof, bolts for connecting the same together, a primary supporting member held by said support, a secondary supporting member borne by the said primary member, and spring means in relation to the said primary and secondary supporting members adapted to absorb 120 125 130

- shock and jar, and a tertiary supporting member, the said primary supporting member being adjustable longitudinally.
4. The combination of a support, a plate running longitudinally thereof, bolts for connecting the same together, a primary supporting member held by said support, a secondary supporting member borne by the said primary member, and spring means in relation to the said primary and secondary supporting members adapted to absorb shock and jar, and a tertiary supporting member, the said primary member being adjustable longitudinally, the said secondary member being adjustable laterally, and the said tertiary member being adjustable vertically.
5. The combination of a support, a plate running longitudinally thereof, bolts for connecting the same together, a primary supporting member held by said support, a secondary supporting member borne by the said primary member, and spring means in relation to the said primary and secondary supporting members adapted to absorb shock and jar, and a tertiary supporting member, the said primary, secondary and tertiary supporting members being adjustable in different directions.
6. The combination of a support, a plate running longitudinally thereof, bolts for connecting the same together, a primary supporting member held by said support, a secondary supporting member borne by the said primary member, and spring means in relation to the said primary and secondary supporting members adapted to absorb shock and jar, and a tertiary supporting member, the said primary, secondary and tertiary supporting members being adjustable in different directions, the said tertiary supporting member being a screw.
7. The combination of a support, a plate running longitudinally thereof, bolts for connecting the same together, a primary supporting member held by said support, a secondary supporting member borne by the said primary member, and spring means in relation to the said primary and secondary supporting members adapted to absorb shock and jar, and a tertiary supporting member, the said primary, secondary and tertiary supporting members being adjustable in different directions, the said secondary supporting member being a slidable rod.
8. The combination of a support, a plate running longitudinally thereof, bolts for connecting the same together, a primary supporting member held by said support, a secondary supporting member borne by the said primary member, and spring means in relation to the said primary and secondary supporting members adapted to absorb shock and jar, and a tertiary supporting member, the said primary, secondary and
- tertiary supporting members being adjustable in different directions, the said secondary supporting member being a slidable rod and having an arm extending therefrom.
9. The combination of a support, a plate running longitudinally thereof, bolts for connecting the same together, a primary supporting member held by said support, a secondary supporting member borne by the said primary member, and spring means in relation to the said primary and secondary supporting members adapted to absorb shock and jar, and a tertiary supporting member, the said primary, secondary and tertiary supporting members being adjustable in different directions, the said primary supporting means being an angle-plate.
10. The combination of a support, a plate running longitudinally thereof, bolts for connecting the same together, a primary supporting member held by said support, a secondary supporting member borne by the said primary member, and spring means in relation to the said primary and secondary supporting members adapted to absorb shock and jar, and a tertiary supporting member, the said primary, secondary and tertiary supporting members being adjustable in different directions, the said primary supporting means being an angle-plate adapted to rest upon part of the said support and also to be held in connection therewith by the said longitudinal plate.
11. The combination of a support, a plate running longitudinally thereof, bolts for connecting the same together, a primary supporting member held by said support, a secondary supporting member borne by the said primary member, and spring means in relation to the said primary and secondary supporting members adapted to absorb shock and jar, and a tertiary supporting member, the said primary, secondary, and tertiary supporting members being adjustable in different directions, the said tertiary supporting member being a screw, and a plate containing screw threads and adapted to move upon the said screw, furthermore being adapted to reversal for holding purposes.
12. In a device of the character described the combination with a support of an angle-plate borne thereby, a holding means attached to the said support and adapted to hold the said angle-plate, a block underlying the said angle plate, another block or plate in connection therewith, a rod adapted to be held between the said last two mentioned members, a U-bolt adapted to bind the said two members and the said rod together, spring means in connection with the said U-bolt adapted to absorb shock and jar upon the said rod, nuts adapted to draw the said U-bolt, and means connected with the said rod suitable for supporting an object.
13. In a device of the character described

- the combination with a support of an angle-plate borne thereby, a holding means attached to the said support and adapted to hold the said angle-plate, a block under-
lying the said angle-plate, another block or plate in connection therewith, a rod adapted to be held between the said last two men-
tioned members, a U-bolt adapted to bind the said two members and the said rod together, spring means in connection with the said U-bolt adapted to absorb shock or jar upon the said rod, nuts adapted to draw the said U-bolt, and means connected with the said rod suitable for supporting an object, the said means comprising an angle-plate hav-
ing screw threads through it and being adapted to move in either direction and there being a screw connecting the same to the said rod.
14. In a device of the character described the combination with a support of an angle-plate borne thereby, a holding means attached to the said support and adapted to

hold the said angle-plate, a block under-
lying the said angle-plate, another block or 25 plate in connection therewith, a rod adapted to be held between the said last two men-
tioned members, a U-bolt adapted to bind the said two members and the said rod together, 30 spring means in connection with the said U-bolt adapted to absorb shock or jar upon the said rod, nuts adapted to draw the said U-bolt, and means connected with the said rod suitable for supporting an object, the 35 said means comprising an angle-plate hav-
ing screw threads through it and being adapted to move in either direction and there being a screw connecting the same to the said rod, and there being nuts adapted to maintain a fixed relation between the said 40 rod and the said screw.

In testimony whereof we hereunto affix our signatures.

ISIDOR M. JACOBS.
WILLIAM CRAMER.
